UNITED STATES PATENT OFFICE.

ROBLEY EUGENE HELLER, OF ABINGDON, ILLINOIS.

RAILWAY-TIE.

SPECIFICATION forming part of Letters Patent No. 738,681, dated September 8, 1903.

Application filed December 29, 1902. Serial No. 137,054. (No model.)

To all whom it may concern:

Be it known that I, ROBLEY EUGENE HELLER, a citizen of the United States, residing at Abingdon, in the county of Knox and State of Illinois, have invented a new and useful Railway-Tie, of which the following is a specification.

This invention relates to metal railway-rail ties, and has for its object to produce a simply constructed and durable tie which will possess sufficient elasticity to yield under the weight of the passing trains to effect a saving in the wear of the rolling-stock, but also decrease the jar and concussion and increasing the comfort of passengers.

The invention consists in certain novel features of construction, as hereinafter shown and described, and specified in the claims.

In the drawings illustrative of the invention, in which corresponding parts are denoted by like designating characters in all the figures, Figure 1 is a longitudinal sectional elevation, and Fig. 2 is a transverse sectional elevation, showing one embodiment of the invention. Figs. 3 and 4 are transverse sectional views illustrating modified forms of the structure.

The improved tie consists in a metal base member constructed in elongated box-like form open at its upper side and with its side, end, and bottom walls of sufficient strength to withstand the pressure to which it will be subjected. In practice the bottom portion (indicated at 10) is somewhat thicker than the sides and ends, (indicated, respectively, at 11, 12, 13, and 14.) The base members will rest upon the ground and will conform substantially in outline to an ordinary tie and will preferably be spaced apart and embedded in the ballast in the ordinary manner relative to the road-bed and rails. Within the base member will be inserted another box-like intermediate member corresponding to the base member and resting by its bottom

member 15 upon the bottom member 10 and with its side and end walls 16, 17, 18, and 19 parallel to and spaced from the side and end walls 11, 12, 13, and 14, as shown, leaving a space between the side and end walls of the two structures, as shown. A third box-like member is provided with a top member 20 and side and end walls 21, 22, 23, and 24,

adapted to fit in the cavity between the base member and intermediate member by its side and end walls, as shown, the top member thus telescoping relative to the base and intermediate member. 55

Within the cavity between the base and intermediate members is inserted a rubber or other suitable packing or cushion 25, with 60 which the edges of the side and end walls of the top member engage when the parts are assembled, as shown. A similar yieldable cushion 26 may also be placed between the upper edges of the side and end walls of the 65 intermediate member and the upper portion of the top member, as shown.

Beneath the points where the rails 27 28 engage the tie the top portion 20 of the upper member is formed thicker, as indicated at 70 29 30, and within the outer surface of the portion 20, opposite these reinforcing portions, are formed cavities or recesses having "dovetailed" or undercut side edges and adapted to receive clamp-plates 31, 32, 33, and 34, the 75 latter having vertical ribs embracing opposite sides of the tie-flanges of the rails, as shown, and by which means the rails are secured in place upon the ties. This portion of the device is the same as disclosed by Patent No. 80 652,265, issued to me on the 26th day of June, 1900, and is not, therefore, further described.

Within the intermediate member between the reinforcing portions 29 30 and the bottom portion 15 of the intermediate member are arranged springs 35 36, the springs being heavy enough to resist the strains of an ordinary train, but which will yield to abnormal pressure, and thus prevent the breakage of the parts. 85 90

Any suitable form of spring and any suitable number of springs may be thus employed; but ordinary coiled springs are shown for illustration, one beneath each of the reinforcing portions 29 30. 95

The area between the intermediate member and top member is filled with air or liquid under pressure, and a suitable cavity filled by a valve 37 will be provided to permit the compressing apparatus to be attached in any suitable manner, and to prevent this air or liquid pressure from separating the parts clamping-bands 38 39 40 will be secured around the assembled structure at suitable intervals to hold 100

the parts from expansion, while at the same time leaving them free to be compressed to a limited extent. The supporting-bands will preferably be attached to the base member, 5 as by bolts 41 42 43, as shown, and will be of sufficient strength to withstand the pressure to which they will be subjected. By this arrangement a very compact and strong tie is produced, which will efficiently resist all 10 strains to which it will be subjected, while at the same time possessing sufficient elasticity to yield to the pressure of the passing trains and prevent undue jar or concussion and cause the cars to run with a smooth gliding motion 15 free from the annoying and unpleasant jolting and swaying so common in running over the ordinary road-bed employing rigid and unyielding ties.

The springs 35 36 will be of sufficient 20 strength to maintain the upper member normally yieldable against the ordinary impact of passing trains, and consequently under such ordinary conditions the parts will not come in contact; but in event of the device 25 being subjected to abnormal pressure the parts will be of sufficient strength to resist the strains and prevent a collapse of the structure when the adjacent parts come in contact.

30 Under some circumstances the intermediate member of the structure may be dispensed with and dependence placed upon the base member and upper member only, as shown in Fig. 3, or the upper member may be arranged 35 with its side and end walls outside the corresponding side and end walls of the base member, as shown in Fig. 4; but these modifications would not be a departure from the principle of the invention, as the results produced and the manner of operation would be 40 the same in all the forms shown.

When the modification shown in Fig. 4 is used, the rubber packing 26 only will be employed, and when the modification shown in 45 Fig. 3 is employed the packings 25 only will be used. The members of the structure will preferably be of cast metal, but may be of other material, if preferred, as any material which may be rendered air or liquid tight may be 50 employed for this purpose. The rubber packings form means for effectually sealing the joints between the parts, the elasticity of the packing maintaining the integrity of the joints at all times and during all the various 55 relative positions of the parts.

It is obvious that any suitable material or compound which possesses the requisite elasticity other than rubber may be employed for the packing means, and I do not, therefore, 60 wish to be limited to any specific material for this purpose. The hollow members will preferably be coated or impregnated with suitable protecting compounds or compositions to prevent corrosion, and the packing-strips 65 will be cemented in place to support them while the fluid-filling is being inserted. Under some circumstances the side and end walls

of the intermediate member may be shortened or formed to extend only a portion of the distance above the portion 10 of the base member. 70

It will be understood that means other than the binding-bands may be employed for supporting the parts, and it will also be understood that in assembling the parts it will be necessary to forcibly compress them, owing 75 to the great expansive force of the springs 35 36 when placing the bands in position. The filling element may be of any suitable material or compound or composition and may consist of air or liquid under pressure or other 80 suitable substance or element under normal pressure. The parts may be formed of any relative size or of any suitable material and may be modified in minor particulars without departing from the principle of the invention 85 or sacrificing any of its advantages.

Having thus described the invention, what I claim is—

1. A railway-tie formed of reversely-disposed hollow members supporting the rails 90 and having their end and side walls movably interengaging, yieldable packing means between the contiguous surfaces of said members, and an elastic filling, substantially as described. 95

2. A railway-tie formed of reversely-disposed hollow members supporting the rails and having their end and side walls movably interengaging, yieldable packing means between the contiguous surfaces of said members, and an elastic fluid-filling, substantially as described. 100

3. A railway-tie formed of reversely-disposed hollow members supporting the rails and having their end and side walls movably 105 interengaging, yieldable packing means between the contiguous surfaces of said members, clamping means connecting said members and preventing their relative outward movement, and an elastic filling, substantially as described. 110

4. A railway-tie formed of reversely-disposed hollow members supporting the rails and having their end and side walls movably interengaging, yieldable packing means between the contiguous surfaces of said members, springs between said members, and an elastic fluid-filling, substantially as described. 115

5. A railway-tie comprising a hollow base member having a relatively thick bottom portion and thin side and end walls, an upper member having a relatively thick top portion and thin side and end walls with said respective side and end walls movably interengaging, means for supporting the rails upon said 120 upper member, yieldable packing means between the contiguous portions of said members, and an elastic filling, substantially as described.

6. A railway-tie, comprising a hollow base 130 member, an intermediate hollow member within said base member with its side and end walls spaced from the side and end walls of said base member, an upper hollow mem-

ber disposed with its side and end walls depending between said spaced side walls of said base and intermediate members, yieldable packing between the contiguous surfaces of said hollow members, and an elastic filling, substantially as described.

7. A railway-tie formed of reversely-disposed hollow members supporting the rails and having their end and side walls movably interengaging, yieldable packing means between the contiguous surfaces of said members, binding-straps embracing said members and preventing relative outward movement, and an elastic filling, substantially as described.

8. A railway-tie formed of reversely-disposed hollow members supporting the rails and having their end and side walls movably

interengaging, binding-straps embracing the members and preventing outward relative movement, and an elastic filling, substantially as described.

9. A railway-tie formed of reversely-disposed hollow members supporting the rails and having their end and side walls movably interengaging, distending springs within said hollow members, and binding-straps embracing the members and limiting the relative outward movement, substantially as described.

In testimony that I claim the foregoing as my own I have hereto affixed my signature in the presence of two witnesses.

ROBLEY EUGENE HELLER.
